DESK BASE FOR A WRITING INSTRUMENT

Walter Irion Bieger, Janesville, Wis., assignor to The Parker Pen Company, Janesville, Wis., a corporation of Wisconsin

Filed Mar. 19, 1959, Ser. No. 55,061

Term of patent 14 years

(Cl. D74—1)

FIG. 1 is a top plan view of a desk base for a writing instrument embodying my new design;

FIG. 2 is a front elevational view of said base;

FIG. 3 is a perspective view thereof, the dotted line partial showing of a writing instrument being for illustrative purposes only; and

FIG. 4 is a cross sectional view thereof taken on the line 4—4 of FIG. 3.

I claim:

The ornamental design for a desk base for a writing instrument, as shown and described.
